[57] CLAIM

The ornamental design for a golf motorcaddie, as shown and described.

DESCRIPTION

FIG. 1 is a front, left side perspective view of a golf motorcaddie showing our new design;

FIG. 2 is a right side view in elevation thereof;

FIG. 3 is a top plan view thereof; and,

FIG. 4 is a rear view in elevation thereof.

The broken lines are environmental only and form no part of the claimed design.

FIG. 1

FIG. 2

FIG. 3

FIG. 4
